US0D1082515S

(12) United States Design Patent (10) Patent No.: US D1,082,515 S
(45) Date of Patent:  Jul. 8, 2025

(54) COSMETIC PACKAGING

(71) Applicant: Maniko Nails GmbH, Berlin (DE)

(72) Inventor: Julia Sherman, Grevenbroich (DE)

(73) Assignee: Maniko Nails GmbH, Berlin (DE)

() Term: 15 Years

(21) Appl. No.: 29/930,367

(22) Filed: Feb. 29, 2024

(30) Foreign Application Priority Data

Sep. 1, 2023 (EM) 015032850-0001

(51) LOC (15) Cl. 09-03

(52) U.S. Cl.

USPC D9/418; D9/414

(58) Field of Classification Search

USPC D9/414, 415, 416, 418, 421, 423, 431, D9/432, 434, 455, 456, 457; D3/201, D3/203.1, 203.2, 203.5, 203.6, 203.8; D20/22, 23, 27, 32, 42; D28/4, 56, 57, D28/73, 76, 83, 84
